UNITED STATES PATENT OFFICE.

GEORGE E. SHORTER, OF WASHINGTONVILLE, NEW YORK.

IRONING-TABLE

1,071,961.

Specification of Letters Patent.

Patented Sept. 2, 1913.

Application filed July 23, 1912. Serial No. 711,150.

To all whom it may concern:

It is known that I, GEORGE E. SHORTER, a citizen of the United States, residing at Washingtonville, in the county of Orange 5 and State of New York, have invented new and useful Improvements in Ironing-Tables, of which the following is a specification.

My invention relates to ironing tables.

The object of my invention is to provide 10 a novel construction of device of this kind made in a plurality of foldable sections, so that when knocked down the parts will occupy a minimum amount of space so that the same can be put in a secluded place until 15 it is again desired to use the same.

The invention consists in the novel construction of parts hereinafter described and illustrated in the accompanying drawings.

In these drawings:—Figure 1 is a perspective view of the device. Fig. 2 is a detail perspective view of one of the major portions of the ironing-board sections, and, Fig. 3 is a detail side view of the major portion of the support section.

Referring to the drawings, the letter A 25 designates an ironing-board section and B designates a support section therefor which is separate therefrom.

The ironing-board section A comprises an ironing board proper 1, which has one end 30 provided with elongated slots 2 in which are located props 3. To the bottom of the ironing-board 1 is secured a plurality of brackets 4, supporting a transverse rod 5 which passes through the props 3 and forms 35 a pivot or hinged joint therefor. The brackets 4 are located at such a distance away from the slotted end of the ironing-board as to provide projections 6 whose 40 function will hereinafter appear. A transverse rod such as 7, may connect the props 3 adjacent their free end. At the upper ends of the props suitable notches 8 are provided to form shoulders for the purpose 45 which will hereinafter appear.

The section B comprises side bars 9 which are bridged by a transverse bar 10 intermediate the ends thereof, and by transverse bars 11 and 12 at one end thereof. A transverse bar 13 secured against the bar 10 projects above said bar. On pivots 14 passing through the bars 9 is hinged a frame generally designated 15. The frame 15 specifically comprises side bars 16 which are 55 connected at one end by a transverse bar 17.

When the device is knocked down the

props 3, by means of the construction shown, may be folded or swung back flat against the bottom of the ironing-board section 1, and the frame 15 of the support section B 60 may be swung down against the side bars 9 of the support section so that said parts will occupy small space when not in use.

In assembling the device, the frame 15 is 65 swung or raised to vertical position as shown in Fig. 1, where its bars 16 abut against the transverse bar 11 which maintains the same in vertical position in combination with the parts to be now referred to. The props of the ironing-board section, are 70 then swung to the position shown in Fig. 1, and the projections 6 inserted under the transverse bar 17, the shoulders at notches 8 brought to engage the bar 17, and the props brought to rest upon the bar 10 and 75 against the upwardly projecting portion of the bar 13. In this position it will be seen that the sections are securely and removably braced to each other.

An auxiliary ironing-board device, such 80 as one used for sleeves, collars or the like, is pivoted at 18 to the bar 17 and comprises an auxiliary ironing-board 19, to the bottom of which is secured a block or riser 20 adapted to rest upon the ironing-board 1. Said 85 auxiliary ironing-board when in use, is in the position shown in Fig. 1, and when not in use may be swung from said position to the position shown in Fig. 3.

Changes within the spirit and scope of the 90 appended claims are of course reserved.

Having thus described my invention, what I claim is:

1. In a device of the class described, an ironing-board section comprising an ironing-board, prop means pivoted thereto, a support section separate from said section having a foldable support member, said prop means engageable with said support section and support member adjacent opposite ends, 95 abutment means for said support member in upright position, and said ironing-board having a portion engaging said foldable section.

2. In a device of the class described, an 100 ironing-board section comprising an ironing-board, prop means pivoted thereto, a foldable support section separate from said section having a pivoted frame, a transverse member thereon, abutment means to limit 105 the pivotal movement of said frame to upright position, a second transverse member

on said section, said prop means engageable with both of said transverse members, and said ironing-board having a portion engaging said first transverse member.

- 5 3. In a device of the class described, an ironing-board section comprising an ironing-board provided with an elongated slot, a prop movable in said elongated slot, pivot means on the ironing-board for the prop, 10 said prop provided with a shoulder, a support section having a pivoted frame provided with a transverse member, said ironing-board section having a portion projecting beyond said pivot and engaging beneath 15 said transverse member, said shoulder engaging said transverse member, and a transverse abutment member on said support section for said prop.
4. In a device of the class described, an ironing-board section comprising an ironing-board provided with a plurality of elongated slots, prop members movable in said elongated slots, pivot means on said ironing-board for said props, means connecting said 25 props together, a support section having a pivoted frame provided with a transverse bar, said ironing-board having a portion

projecting beyond the pivot means and engaging beneath said transverse bar, said props provided with shoulders to engage 30 said transverse bar, a transverse abutment member for said props, and abutment means for said pivoted frame.

5. In a device of the class described, an ironing-board section comprising an ironing-board provided with an elongated slot, a prop movable in said slot, pivot means on the ironing-board for said prop, said prop provided with a shoulder, a support section having side bars, a frame having side bars 40 pivoted to the side bars of the support section, a transverse bar connecting the side bars of the frame, a transverse bar against which the frame side bars abut, said shoulder of the prop engaging said first named 45 transverse bar, said ironing-board extending below and against said transverse bar, and a transverse bar connecting the side bars of the support section and against which the prop abuts.
